NEEDLE FOR AXMINSTER LOOM

Clyde E. Brown, Grafton, Mass., assignor to
Crompton & Knowles Loom Works, Worcester,
Mass., a corporation of Massachusetts

Application July 15, 1940, Serial No. 345,541

4 Claims. (Cl. 139—123)

This invention relates to weft laying needles for Axminster looms and it is the general object of the invention to provide a needle having an eye which will withstand the wearing action of the weft.

Axminster looms ordinarily employ an elongated needle having an eye through which the weft is led from a stationary supply. The needle is generally formed of a tube into the end of which is fitted an eye section which has been formed of a solid rod perforated to define the eye. Axminster fabrics are customarily woven with jute filling which has a rapid wearing action on the needle eye. It is an important object of my present invention to secure a vitreous or porcelain eye into the needle by a method which does not injure the porcelain. I carry my invention into effect by providing the porcelain eye with a peripheral groove into which is placed a body of metal which can be soldered to the needle eye section. This body of metal may either be a band, ring, or coil of wire, but whatever the form of this body of metal it will have a surface to which solder or the like will adhere. The solder melts at a temperature considerably lower than that necessary to destroy the glazed surface of the porcelain and for this reason the porcelain eye is not affected by the heating operation by which it is secured to the eye section.

My invention relates also to a needle having a porcelain eye held in place on the needle by a body of metal fused to the needle and extending into a groove or the like in the eye.

With these and other objects in view which will appear as the description proceeds, my invention resides in the combination and arrangement of parts hereinafter described and set forth.

In the accompanying drawing, wherein two forms of my invention are set forth,

Fig. 1 is a front elevation of one end of an Axminster needle made according to the preferred form of my invention,

Fig. 2 is an enlarged plan in the direction of arrow 2, Fig. 1,

Fig. 3 is an enlarged vertical section on line 3—3 of Fig. 2,

Fig. 4 is a front elevation of the porcelain eye shown in Fig. 3 before attachment to the needle,

Fig. 5 is a plan view of a modified body of metal which may be used instead of the coiled wire of the preferred form, and

Fig. 6 is an end view taken in the direction of arrow 6, Fig. 5.

Referring to the drawing, the needle N is formed of the customary tube 10 into which pro-

jects the shank 11 of a needle section 12. The section 12 has a head 13 through which extends a bore 14 proportioned to receive a vitreous or porcelain eye 15. The latter as shown in Fig. 4 is of a generally cylindrical form but has cut into the edge thereof a peripheral circular groove 16 the effect of which is to provide the central longitudinal part or neck of the eye with a reduced diameter indicated at 17. The top and bottom 18 and 19, respectively, of the porcelain eye is wider than the neck 17, and there is extending entirely through the eye an aperture 20 for the reception of the weft thread W. The aperture 20 and the outer surfaces of the top and bottom 18 and 19, respectively, are glazed to provide a hard wear resistant surface.

In carrying my invention into effect I surround the narrow neck portion 17 with a body of metal designated generally at 25. In the preferred form this metal may be a copper or steel wire wound around the neck 17 to a depth sufficient to establish holding frictional contact with the bore 14. The eye is then forced into the bore and solder is caused to flow into the space between the bore 14 and the top and bottom of the porcelain eye and also into contact with the coiled wire. The solder adheres to and flows around the wire to encircle the neck 17 with a substantially solid mass of metal which is integral with other metal held tightly to the bore 14 by the soldering operation, as indicated in Fig. 3. The solder will also lie between the bore 14 and the wider parts of the eye above and below the neck 17, as shown in Fig. 3, to resist twisting of the eye relatively to the needle.

Instead of the coiled wire, I may employ an open ring 30 as indicated in Fig. 5 as a modification. This ring can be spread to fit around the neck 17 and then be closed sufficiently to lie in the groove 16 but be large enough to be held frictionally in bore 14. The ring is then soldered in the bore in a manner similar to that already described.

A needle formed according to my present invention will have practically the whole of the groove 16 filled with fusible metal which is firmly attached to the needle and for this reason the porcelain eye is held in fixed position in the section 12.

From the foregoing it will be seen that I have provided an Axminster loom needle wherein the yarn eye is formed of porcelain and is held to the needle by a mass of metal adhering to a bore in the needle and extending into portions of the eye. It will also be seen that I have provided a

needle eye a portion of which is surrounded by a solderable metal and attached by a fusible metal to the walls of the bore 14. It will further be seen that I have provided a method wherein the non-metallic porcelain eye can be held in position on the needle by metal which melts at the sufficiently low temperature to avoid fracture or damage to the eye. Also, the method is facilitated by having the body of metal, either the coiled wire or ring, frictionally engage the walls of bore 14 to hold the eye in position during the soldering operation. While I have specifically described soldering as the means for attaching the eye to the needle I do not wish necessarily to be limited to this procedure, since any of the brazing compounds which melt at a sufficiently low temperature can be substituted for solder.

Having thus described my invention it will be seen that changes and modifications may be made therein by those skilled in the art without departing from the spirit and scope of the invention and I do not wish to be limited to the details herein disclosed, but what I claim is:

1. A needle for an Axminster loom having a metallic body with a bore extending therethrough, a cylindrical vitreous eye element in the bore having a zone of reduced diameter, a body of metal surrounding and extending into the zone of reduced diameter, and a mass of fusible metal connecting the body of metal to the walls of said bore.

2. An Axminster loom needle having a body through which extends an eye receiving bore, a vitreous eye element having a peripheral groove formed therein, a body of metal located in said groove, and a fusible metal adhering to the walls of the bore and also to said body of metal and extending into said groove to hold the body of metal and the eye element in fixed position on the needle.

3. In an Axminster loom needle having a metallic body through which a bore extends, a porcelain eye member located in the bore and having a peripheral groove therearound, a body of metal located in said groove, and a fusible material adhering to the walls of the bore and also to said body of metal in the groove and having contact with portions of the eye element to hold the latter in fixed position with respect to the needle.

4. A needle for an Axminster loom having a metallic body with a bore extending therethrough, a cylindrical vitreous eye element in the bore having a zone of reduced diameter, a body of metal surrounding and extending into the zone of reduced diameter, and a mass of fusible metal connecting the body of metal to the walls of said bore the body of metal having close frictional engagement with the walls of the bore which acts supplementally to the fusible metal to resist motion of the body of metal longitudinally in the bore.
